UNITED STATES PATENT OFFICE

2,642,194

FOLDABLE NECKTIE RACK

Matthew P. Boltauzer, Willoughby, Ohio

Application June 17, 1950, Serial No. 168,725

1 Claim. (Cl. 211—104)

1

My invention relates to a new design and useful improvement in devices for holding neckties.

The primary object and purpose of this invention is to provide a device in the nature of a rack for holding a desired number of neckties.

Another object and purpose of the invention is the provision of a rack as described that is adapted to be extended from its folded form so as to provide means for holding a larger number of neckties, when so desired.

A further object and purpose of the invention is the provision of a necktie rack as described that embodies a base, or supporting member with an extendable member supported on each end of the supporting member.

A still further object and purpose of the invention is the providing of a device as described that is simple and inexpensive in structure.

The foregoing stated objects and purposes and others attainable by the use of the invention will be readily observed by a reading of the description herein, in conjunction with the accompanying drawing, in which:

The Figure is a perspective view of the invention in its fully extended form.

Describing the invention from the drawing:

The numeral 1 designates the body, or supporting base member of the device, 2 are extendable members or arms attached to 1 by means of U-shaped supports 5 and pivots 5A, such members are adapted to be folded in against the member 1 when desired, the members 1 and 2 are provided with a plurality of pins 4 fixed upright in the upper surface of the members 1 and 2 and at regular or uniform intervals or spaces. 3 are supports for attaching to a wall or other supporting surface by means of screws, etc., inserted through the opening 3A, the device being attached to the supports 3 by means of bolt 6.

The pins 4 are properly spaced to allow a necktie to be placed between any two of them without wrinkling such tie. The extendable members or arms 2 are pivotally supported within the U-shaped support 5 or integral end portions of base member 1 by means of the bolt or pivot 5A and may be folded inwardly to a position in spaced relation and parallel to the base member 1, and when in such position, the pins 4 in the members or arms 2 are in alinement with the pins 4 in the base or supporting member 1 thus providing double supporting spaces for neckties.

As shown and described it will be understood that the base or supporting member 1 is provided at each end with U-shaped means 5 for attaching the members 2 therein and fixed therein by

2

5A in such a manner that they can be swung outward into a position extending in the same direction with the base, or supporting member 1, to provide rack space for a larger number of neckties than when such members are in their closed position, folded in and against the base, or supporting member 1 and with the pins 4 in such members 2 in alinement with the pins 4 on the member 1, when in such folded position.

10 The device is adapted to be attached on, or to a supporting surface by means of the members, 3, such as a door, wall, or similar surfaces.

The device may be made of any desirable and suitable material, such as plastic, wood, etc., and 15 of such size or length as to provide space for a plurality of pins for the hanging of any number of neckties.

I have shown my device in an exemplary form and structure, however adaptations in use may 20 require modifications or changes in design or structure, or both without departing from the basic features or the spirit of the invention.

What I desire to secure by Letters Patent, is:

A necktie rack adapted to be horizontally 25 fastened to a wall for holding neckties, said rack comprising, a single elongated supporting base member having opposite ends and a front, top, and back surface, a pair of supports, one secured on each end of said base member and adapted 30 to hold said base member at a distance from the wall, a pair of vertically spaced integral end portions on each end of said front surface and extending forwardly therefrom and at right angles thereto, two straight arms each having 35 a length equal to one-half the length of the base member and having one end pivoted to a pair of said end portions to position said arms in spaced relation and parallel to the base member when the arms are hingedly moved into an 40 end to end straight line formation between the end portions, said arms and said base member having a plurality of pins extending vertically upwardly from the top surfaces thereof with the pins equally spaced apart.

MATTHEW P. BOLTAUZER.
